UNITED STATES PATENT OFFICE.

CHARLES EDWARD HARKER, OF PARNASSUS, PENNSYLVANIA, ASSIGNOR TO ELECTRIC
RENOVATOR MANUFACTURING COMPANY, OF PITTSBURG, PENNSYLVANIA, A COR-
PORATION OF PENNSYLVANIA.

DESIGN FOR A CASING FOR PNEUMATIC CLEANING-MACHINES.

40,848.

Specification for Design.

Patented Aug. 30, 1910.

Application filed August 2, 1909. Serial No. 510,955. Term of patent 14 years.

To all whom it may concern:

Be it known that I, CHARLES EDWARD HARKER, a citizen of the United States, residing at Parnassus, county of Westmoreland, and State of Pennsylvania, have invented a new, original, and ornamental Design for a Casing for Pneumatic Cleaning-Machines, of which the following is a specification, reference being had to the accompanying drawing, forming part thereof.

The figure is a perspective view of a casing for pneumatic cleaning machines, showing my new design.

I claim:

The ornamental design for a casing for pneumatic cleaning machine, as shown.

CHARLES EDWARD HARKER.
